UNITED STATES PATENT OFFICE.

CHARLES A. MANN, OF BUFFALO, NEW YORK.

BARBED-WIRE FENCE.

SPECIFICATION forming part of Letters Patent No. 276,439, dated April 24, 1883.

Application filed January 10, 1883. (No model.)

To all whom it may concern:

Be it known that I, CHARLES A. MANN, a citizen of the United States, residing at Buffalo, in the county of Erie and State of New York, have invented certain new and useful Improvements in Barbed-Wire Fences; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to that class of barbed fence-wire which is made from a flat metal strip, and it consists substantially in cutting the barbs from a continuous portion turned up from one edge of the flat strip, and bending them in opposite directions in the plane of the strip proper.

Another feature of my invention consists in so forming the strip, after the barbs have been cut and bent, that there will be two lines of barbs lying substantially in parallel planes.

My invention further consists of other details of construction, which will be more fully hereinafter described and claimed.

In the drawings, Figure 1 is a perspective view of the metallic strip, illustrating the manner of cutting the barbs. Fig. 2 is a similar view illustrating the manner of bending the barbs. Fig. 3 is an end view of Fig. 2. Fig. 4 is a perspective view illustrating another step in the invention. Fig. 5 is an end view of Fig. 4, and Fig. 6 is a view of a fence embodying my invention.

Referring to the drawings, in Fig. 1, *a* is the strip proper, and *a'* is the turned-up portion integral with the strip *a*. This angular strip is preferably of steel, and is formed between rolls in the usual manner. The turned-up portion *a'* is located at one edge of the strip proper, *a*, as shown in the drawings. Having formed the strip in this manner, I next cut the turned-up portion *a'* at the lines *b b* and *c c*, (see Fig. 1,) forming the pointed barbs *d* and *e*. I next bend these pointed barbs *d* and *e* in opposite directions on the dotted lines *d'* and *e'*, (see Fig. 1,) so that they are at substantially right angles to the strip proper, as clearly shown in Fig. 2, the barbs *e* extending across and be-

yond the strip proper. After the strip is formed, as shown in Fig. 2, I preferably galvanize it, in which event the barbs *e*, which lie against the surface of the strip proper, are securely united thereto by the zinc or other material employed in the galvanizing process, and thereby serve to materially strengthen such strip, for the reason that the portions of the barbs *e* lying against and secured to the strip proper form transverse strengthening-ribs *e'*, and additionally prevent the barbs *e* from being bent out of position. The parts *f* of the turned-up portion *a'*, which are not disturbed in the cutting and bending of the barbs, serve as strengthening-pieces for the strip proper.

It will thus be seen from the foregoing description that no waste of material is involved in the manufacture of my improved fence-wire, all portions of the angular strip, when formed into the barbed wire, possessing separate and important functions. The barbed strip is attached by means of staples to posts to form the fence, as shown in Fig. 6, with the barbs standing vertically in opposite directions. The strips are not twisted in forming the fence, which has the effect of rendering it comparatively harmless, except in the event of the animal's attempting to force itself through.

In order to prevent animals from rubbing against the fence in such a manner as to injure it by breaking the strips, I have provided it with a series of transverse bends or curves, *g*, so located, as clearly shown in Fig. 4, as to throw a number of pairs of the barbs out of line with the strip proper, thus forming two lines of barbs lying in substantially parallel planes, as shown in Fig. 5. The barbs in the bends *g* have the effect of preventing the animals from rubbing against and breaking the strip, without at the same time causing them serious injury, as is the case in fences where the strips or wires are twisted in such a manner that the barbs point in all directions.

I claim—

1. In a wire fence, a flat metal strip having a continuous portion or flange turned up from one edge of the flat strip, from which a series of barbs are cut and bent in opposite directions in the plane of the strip proper, substantially as shown and described.
2. In a wire fence, a flat metal strip having

a turned-up portion or flange integral therewith, and from which a series of barbs are cut and bent in opposite directions in the plane of the strip proper, such strip proper being provided with a series of transverse bends or grooves so arranged as to form two lines of barbs lying in substantially parallel planes, substantially as shown and described.

3. In a wire fence, the flat metal strip *a*, having the longitudinal strengthening portions *f*, and the barbs *d* and *e*, bent in opposite directions in the plane of the strip *a*, the portions *f* and the barbs *d* and *e* being formed from the

turned-up portion or flange *a'*, without waste, and the barbs *e* being securely united by the galvanizing process to the strip *a*, along their lines of contact with such strip, thereby forming the transverse strengthening-ribs *e'*, substantially as shown and described.

In testimony whereof I have signed my name to this specification in the presence of two subscribing witnesses.

CHARLES A. MANN.
